UNITED STATES PATENT OFFICE

WILLIAM E. SLOAN, OF CHICAGO, ILLINOIS

FLUSH VALVE

Application filed April 9, 1927. Serial No. 182,517.

This invention relates to flush valves and has for its object to provide a new and improved valve of this description.

The invention has as a further object to provide a flush valve with a new and improved by-pass construction.

The invention has as a further object to provide a flush valve having exterior means for regulating the valve.

10 The invention has as a further object to provide a flush valve which shall be reliable and accurate in operation and which can be easily constructed and assembled.

15 The invention has other objects which are more particularly pointed out in the accompanying description.

Referring, now, to the drawing, Fig. 1 is a sectional view showing one form of valve embodying the invention.

20 Fig. 2 is a sectional view taken on line 2—2 of Fig. 1.

Fig. 3 is a sectional view showing a modified construction.

25 Fig. 4 is a sectional view showing a further modification.

Fig. 5 is a sectional view showing a further modification.

Like numerals refer to like parts through out the several figures.

30 Referring, now, to the drawing:—

I have shown a flush valve having a casing 1 with a removable end piece 2. This casing is provided with an admission opening 3 and a discharge opening 4. The admission opening is connected with the source of water supply and the discharge opening leads to the point of use of the water. A valve seat 4a is located in the casing. A valve member 5 co-operates with this valve seat and controls the flow of water through the casing. A piston 6 is connected with the valve member 5 and divides the casing into two chambers 7 and 8. The valve is controlled by varying the relative pressure in the chambers 7 and 8. Water passes from the chamber 7 to the chamber 8 to equalize the pressure in the two chambers through a by pass or passageway leading from the chamber 7 to the chamber 8.

45 In the construction shown, this passageway has a laterally extending portion 9 and a portion 10 at an angle thereto. The portion

10 has an enlarged section 11 containing a control member 12 and being provided with a contracted outlet 13. The control member 12 is arranged with a portion 14 which projects into the outlet 13 and beyond the face 55 of the piston 6 when the control member is in its closed position. The control member has a closing face 15 which engages a seat 16 so as to shut off the main flow of water through the by pass. Means is provided for 60 permitting a small flow of water from chamber 7 into chamber 8 when the controlling member is closed.

In the construction shown, this means consists of one or more channels or grooves 17 65 on the closing face 15 of the control member. The control member 12 is normally held against its seat by a spring, or the like, 12a which surrounds the reduced portion of said control member. This reduced portion projects into the passageway 10 but has a smaller cross sectional area than said passageway so that water may flow through the passageway.

70 Means is provided for permitting water to escape from the chamber 8 to secure the operation of the valve. A suitably controlled escape passageway may be provided for this purpose.

75 In the particular construction illustrated, this escape passageway is provided with an 80 enlarged portion 18 with a plurality of branches 19 leading therefrom through the piston 6 to the chamber 8 and an escape opening 20 leading to the discharge opening 4. An escape valve 21 is located in the enlarged 85 portion 18 and normally rests upon a seat 22 so as to close the escape passageway.

85 Some means is provided for operating the escape valve. In the construction shown, this valve is operated by means of a handle 23 90 which is operatively connected with the escape valve in any suitable way.

95 In the particular construction shown, the escape valve is provided with a projecting portion 24. A controlling part 25 is arranged to engage the projecting portion 24, when the handle 23 is moved so as to move the escape valve 21 to open the escape passageway. The controlling part 25 is slidably mounted in a removable piece 26 and has an enlarged end 100

27 which engages the end 28 of the handle, and is normally held in its inoperative position by the spring 29. When the handle 23 is moved in any direction, the controlling piece 25 is thrust forward so as to engage the projecting part 24 and move the escape valve 21 to open the escape passageway. When the handle is released, the spring 29 moves the handle and the controlling piece 25 to their initial positions. The escape valve 21 will return to its initial position. If desired, however, a closing device such as the spring 30 may be provided. In order to facilitate the assembling of the parts, the valve member 5 is made separate from the piston, the piston being provided with a projecting part in which the enlarged portion 18 of the escape passageway is formed and into which the escape valve 21 is received.

20 The valve member 5 is attached to the hollow projection on the piston, by a threaded connection as shown in Fig. 1. In order to provide easy means for inserting the controlling member 12 in position, the piston 6 is provided with a removable portion 6a and the packing piece 6b, for the piston, is clamped thereto by the removable piece 6a and the fastening device 6c.

Means is provided for adjusting the flush valve so that the amount of water discharged each time the valve is operated, may be varied. In the construction shown, this result is accomplished by an adjusting device which controls the amount of movement of the piston 6 and the amount of time the valve member 5 is open. For this purpose there is an adjusting device 31 connected with the casing which is shown as an adjusting screw. This adjusting device is arranged to be projected more or less beyond the face 32 of the casing and is provided with a notch 33 for an adjusting tool to facilitate its adjustment. This adjusting device engages the top of the piston 6 and limits its upward movement. It will be seen that as the portion of the adjusting device which projects beyond the face of the casing, is lengthened, the distance through which the piston moves will be shortened. This reduces the amount of water discharged from the valve in two ways, namely, by reducing the opening produced by the valve member 5 and by shortening the time the valve member 5 is open.

It will be seen that by means of this device, any desired adjustment may be secured. In the construction illustrated, the adjusting device 31 is located so that it will engage the portion 14 of the control member 12 so as to move the control member to engage the passageway leading from the chamber 7 to the chamber 8 and permit a greater flow of water so as to insure against obstruction of the passageway. The adjusting device 31 is provided with a groove 34 at its lower end so that it does not interfere with the flow of the

water from the outlet 13 of said passageway.

In order to prevent unauthorized tampering with the adjusting device, a plug 35 is provided in a screw threaded opening in the casing. If this plug is moved, it does not move the adjusting device. In order to move the adjusting device, the plug must be removed.

In Fig. 3, I have shown a modified construction where the control member 12b is hollow and is held against its seat by the flow of the water in chamber 75.

In Fig. 4 I have shown a further modification where the control member 12c is a float, that is, a device which, when the water enters the chamber in which it is located, will, by its buoyancy be moved to its closed position. 80

Fig. 5 is a further modification showing the control member 12d as a hollow receptacle acting as a float which is, by its buoyancy moved to its closed position confining the flow of the water to the by-pass 17d.

The use and operation of my invention are as follows:— 90

When the valve is in use, the parts, when the valve is not being operated, are as shown in Fig. 1. When it is desired to operate the valve, the handle 23 is moved. This moves the controlling piece 25 and the projecting part 24 and the escape valve 21. Water is now permitted to escape from the chamber 8 through the escape passageway 18, 19 and 20 through the open escape valve 21. This releases the pressure in the chamber 8 and the pressure of the water in chamber 7 moves the piston 6 so as to move the valve member 5 from its seat and permit water to pass from the source of supply through the discharge to the point of use.

When the piston moves up to its upward limit, the adjusting device 31 engages the end 14 of the control member 12 and moves said control member to its open position, that is, so as to separate the faces 15 and 16. When 110 the handle 23 is relieved, the escape valve 21 returns to its closed position so as to cut off the escape of the water from the chamber 8. Water now passes from chamber 9 up through the by pass and past the control member 12 into the chamber 8 equalizing the pressure in the two chambers and causing the piston 6 to be moved back to its initial position. 115

When the piston moves sufficiently to dis- 120
engage the adjusting device 31 from the end
14 of the control member 12, this control
member is moved to its closed position and
the water then passes into chamber 8 through
the groove 17 in the closing face of the con- 125
trol member.

When equalization of the pressure is secured, the valve member 5 is closed. If the handle 23 is now again moved, the operation above described would be repeated. It will 133

be noted that when the valve is operated and the piston moved to its upward limit, the control member 12 in the by pass, is moved so that the seating parts are separated and an enlarged opening provided through which the water rushes. This insures a proper cleansing of the by pass and prevents stoppage thereof by foreign material. This movement of the control member 12 occurs 10 with every operation of the valve and hence the danger of stoppage of the by pass is entirely eliminated.

When it is desired to reduce the amount of water discharged from the flush valve, at 15 each operation, the adjusting device 31 is adjusted to project farther beyond the face 32 of the casing. This reduces the maximum opening of the valve member 5 and shortens the length of time it is open thus reducing 20 the quantity of water discharged. When it is desired to increase the amount of water discharged at each operation of the flush valve, the adjusting device 31 is moved so as to decrease the length projecting beyond the face 25 32. This increases the maximum opening of the valve member 5 and also increases the time during which the valve member 5 is open, thus increasing the amount of water discharged by the valve at each operation.

20 It will further be noted that the by pass is in the moving piston and is at the center of the flow of water so that it is in the swift current of water flowing through the valve and the discharge of any foreign matter from the 25 by-pass is assured. The by-pass may be secured by flattening one of the associated parts so that there will be a space between the two parts to permit the flow of the desired amount of water.

40 **I claim:**

1. A flush valve comprising a casing, a valve member controlling the passageway therethrough, a piston in said casing connected with said valve member, said piston 45 dividing the casing into two chambers and having a passageway therethrough which connects the two chambers, said passageway being enlarged between its ends, a control member located in the enlargement of said passageway, adapted, when in its closed position, to partially close said passageway, means brought into action by the movement of said piston for moving said control member to enlarge said passageway during a part of the 50 movement of said piston, and means separate from said passageway for relieving the pressure in the chamber above said piston when it is desired to actuate the valve member.

2. A flush valve comprising a casing, a 55 valve member adapted to control the passageway through said casing, a piston in said casing connected with said valve member and dividing the casing into two chambers, said piston having a passageway therethrough 60 connecting said chambers, a control member

for controlling said passageway, means for actuating said control member to enlarge said passageway each time the valve is operated, and means separate from said passageway 70 for relieving the pressure in the chamber above said piston when it is desired to actuate the valve member.

3. A flush valve comprising a casing, a valve member adapted to control the passageway through said casing, a piston in said casing connected with said valve member and dividing the casing into two chambers, said piston having a passageway therethrough 75 connecting said chambers, an automatic control member for controlling said passageway, means for actuating said control member to enlarge said passageway each time the valve is operated, an adjusting device for varying the distance through which the piston moves at 80 each operation of the valve, and means separate from said passageway for relieving the pressure in the chamber above said piston when it is desired to actuate the valve member.

4. A flush valve comprising a casing, a valve member for controlling the passageway through said casing, a piston in said casing connected with said valve member, said piston dividing the casing into an upper and a lower chamber, said piston being provided 85 with a passageway therethrough which connects the two chambers, means responsive to the movement of said piston for enlarging said passageway for a predetermined period each time the valve is operated, and means separate from said passageway for relieving the pressure in the chamber above said piston when it is desired to actuate the valve member.

5. A flush valve comprising a casing, a valve member for controlling the passageway through said casing, a piston in said casing connected with said valve member, said piston dividing the casing into an upper and a lower chamber, said piston being provided with a passageway therethrough which connects the two chambers, means responsive to the movement of said piston for enlarging said passageway for a predetermined period each time the valve is operated, means for varying the distance through which the piston moves at 90 each operation of the valve, and means separate from said passageway for relieving the pressure in the chamber above said piston when it is desired to actuate the valve member.

6. A flush valve comprising a casing, a valve member for controlling the passageway through the casing, a piston connected with said valve member and dividing the casing into an upper and a lower chamber, said piston having a passageway therethrough for 95 permitting water to be discharged from the upper chamber, a valve in said passageway, means accessible from the exterior of the casing for controlling said valve, said piston being provided with a second passageway for 100 105 110 115 120 123 128 133

permitting water to flow from the lower chamber to the upper chamber, a control member in said passageway inaccessible from the exterior of the casing, means responsive to the movement of said piston for moving said control member to enlarge said second passageway for a predetermined period each time the valve is operated, and means separate from said passageway for relieving the pressure in the chamber above said piston when it is desired to actuate the valve member.

7. A flush valve comprising a casing, a piston in said casing dividing it into an upper and a lower chamber, a valve member connected with said piston, a seat with which said valve member co-operates, a discharge device beyond said seat, said piston being provided with two passageways, one connecting the upper and lower chambers, the other connecting the upper chamber with said discharge device, and an automatic control member in said first mentioned passageway.

8. A flush valve comprising a casing, a piston in said casing dividing it into an upper and a lower chamber, a valve member connected with said piston, a seat with which said valve member co-operates, a discharge device beyond said seat, said piston being provided with two passageways, one connecting the upper and lower chambers, the other connecting the upper chamber with said discharge device, an automatic control member in said first mentioned passageway, and a valve in said second passageway controlled from the exterior of the casing.

9. A flush valve comprising a casing having an inlet, a piston in said casing dividing it into two chambers one of which communicates with said inlet, a valve member connected with said piston, a valve seat with which said member co-operates, said piston being provided with a passageway connecting the two chambers, having an enlargement intermediate its ends, an automatic control member located in said enlargement, an engaging part which engages said control member and actuates it in opposition to the water pressure after the said valve member has been moved from its seat, said piston being provided with a removable part which holds said control member against removal.

10. A flush valve comprising a casing, having an inlet and an outlet, a piston in said casing dividing it into two chambers, a main valve member connected with said piston, a valve seat with which said main valve member co-operates, a passageway extending through said piston connecting one of said chambers with said outlet, a tilting valve controlling said passageway said passageway being normally open at all points except where the tilting valve closes it and an actuating mechanism for tilting said valve to open said passageway the passageway extending

through said piston and which connects one of said chambers with the outlet being located above the tilting valve, and a bypass having a portion extending centrally through said piston and above said tilting valve.

11. A flush valve comprising a casing, having an inlet and an outlet, a piston in said casing dividing it into two chambers, a main valve member connected with said piston, a valve seat with which said main valve member co-operates, a passageway extending through said piston connecting one of said chambers with said outlet, a tilting valve below said piston controlling said passageway said passageway being normally open at all points except where the tilting valve closes it and an actuating mechanism for tilting said valve to open said passageway, a spring located above said tilting valve, for returning the tilting valve to its closed position, a bypass connecting the two chambers in the casing, said bypass centrally located with relation to the piston and in vertical alignment with said tilting valve.

Signed at Chicago, county of Cook and State of Illinois, this seventh day of April 1927.
